UNITED STATES PATENT OFFICE

MARY H. AITON, OF SUMMER HILL, ILLINOIS

FENCE POST

Application filed April 29, 1930, Serial No. 448,312. Renewed February 27, 1932.

The present invention relates to fence posts and more particularly to a temporary fence post which may be securely positioned in the ground and removed therefrom when desired.

An object of this invention is to provide a fence post of this character which may be inserted in the ground and upon which a screen wire or fence wire may be removably secured.

Another object of this invention is to provide a fence post having outstanding flanges or fins at the lower end thereof so as to limit the insertion of the post in the ground.

A further object of this invention is to provide in combination with a removable fence post, means for pulling the post out of the ground.

The above and various other objects and advantages of this invention will in part be described in and in part be understood from the following detailed description of the present preferred embodiment, the same being illustrated in the accompanying drawings wherein:

Figure 1 is a detail front elevation of a device constructed according to the preferred embodiment of this invention;

Figure 2 is a sectional view taken on the line 2-2 of Figure 1;

Figure 3 is a sectional view taken on the line 3-3 of Figure 1;

Figure 4 is a detail side elevation of the jack member; and

Figure 5 is a fragmentary side elevation of the forked lever.

Referring to the drawing wherein like numerals of reference designate corresponding parts throughout the several views, the numeral 10 designates generally a fence post constructed according to the preferred embodiment of this invention, the post 10 being constructed of metal and being preferably substantially U shaped in cross section and having a pointed lower end 11 which is adapted to be inserted into the ground. The point 11 is formed integrally with the front face 12 of the post and a driving head or cap 13 is positioned on the upper end of the post, the driving head being adapted to protect the

upper end of the post while it is being driven into the ground.

The post 10 is provided with a pair of horizontally disposed wings or stop members 14 which are secured to the post and formed integrally therewith at a point spaced upwardly from the lower end thereof, the fins or wings 14 being adapted to limit the insertion of the point 11 into the ground. The wings 14 may be formed integrally with the opposite sides 15 of the post and may be of any desired length which is sufficient to limit the insertion of the post in the ground.

A wire holding plate 16 is secured to the front face 12 of the post by means of bolts, rivets or the like 17, and the wire securing plate 16 is provided with a plurality of outstanding lugs or arms 18 which are provided with aligned apertures 19 for removably receiving a wire locking pin 20 for removably securing a wire 21 upon the outstanding lugs 18. The lugs 18 are adapted to extend through the mesh of the wire 21 and the locking bar 20 may be provided with a handle or looped upper end portion 22 so as to facilitate removal of the bar from the lugs 18.

The fence post disclosed herein has been particularly designed for holding a wire screen which is adapted to be temporarily placed at the desired point for temporarily enclosing a section of ground, and when it is desired to remove the post from the ground, a stepped jack 23 may be placed against the post 10 and a forked lever 24 positioned on one of the stepped portions of the jack 23 and the forked portions of the lever inserted beneath the outstanding arms 14 of the post whereupon the lever may be rocked upon the jack and the post pulled out of the ground.

In the use of this device, the post 10 may be driven into the ground in the conventional manner and when it has been inserted to the point where the outstanding arms 14 engage the ground, a wire 21 of suitable construction may be positioned on the outstanding lugs 18 of the elongated plate 16, and the securing bar 20 positioned in the aligned apertures 19, it of course being understood that the apertures 19 are positioned at a point spaced outwardly from the outer surface of 100

the plate 16 and so positioned that when the securing bar 20 is inserted in the apertures 19, the wire 21 will be firmly held upon the lugs 18.

5 It will, therefore, be obvious from the foregoing that an exceedingly convenient temporary post has been devised by means of which the wire may be removably positioned upon the post without injuring the wire or 10 injuring the post, and when it is desired to remove or pull the post out of the ground the post may be readily removed by means of the tool in the form of the forked lever and the stepped jack which have also been disclosed. 15 While the wire holding members 18 have been disclosed as formed integrally with the plate 16, it is of course understood that the wire holding members may be formed integrally with the outer face 12 of the post 10. 20 by means of pressing portions of the post outwardly and where this is done the plate member 16 may, of course, be eliminated.

It will, of course, be understood that various changes and modifications may be made 25 in the details of construction and design of the above specifically described embodiment of this invention without departing from the spirit thereof, such changes and modifications being restricted only by the scope of the following claim.

What is claimed is:—

In combination, a fence post, and wire securing means mounted on said post, said wire securing means comprising an elongated 25 plate member bent outwardly intermediate the ends thereof whereby to provide wire supporting lugs, each of said lugs having aligned openings therethrough disposed outwardly from said plate, means for securing 40 said plate to said post, and a wire securing bar positioned in said openings and removably locking the wire on the lugs between the outer face of the plate and the bar.

In testimony whereof I hereunto affix my 45 signature.

MARY H. AITON.
